INVENTOR

Andrew Parrott
BY
G. C. Kennedy,
ATTORNEY

UNITED STATES PATENT OFFICE.

ANDREW PARROTT, OF SUMNER, IOWA.

CARPET-STRETCHER.

SPECIFICATION forming part of Letters Patent No. 681,257, dated August 27, 1901.

Application filed May 13, 1901. Serial No. 59,930. (No model.)

To all whom it may concern:

Be it known that I, ANDREW PARROTT, a citizen of the United States of America, and a resident of Sumner, Bremer county, Iowa, have 5 invented certain new and useful Improvements in Carpet-Stretchers, of which the following is a specification.

My invention relates to improvements in carpet-stretchers; and the objects of my improvement are to provide a greater leverage and corresponding increase of power and also to render the means adjustable to the extent desired. I attain these objects by the means illustrated in the accompanying drawings, in 15 which—

Figure 1 is a side elevation of my improved carpet-stretcher. Fig. 2 is a plan view of the same, and Fig. 3 is a detail view showing the under surface of one of the hook-studded 20 stretcher-pads.

Similar letters refer to similar parts throughout the several views.

The pads *c* and *c'* have a plurality of hooks *f* and *f'* attached to their under surfaces, the 25 hooks in each case being curved outward. Cross-pieces *a* and *a'* are attached, respectively, to the upper surfaces of the pads *c* and *c'* by means of the hinges *e* and *e'*. The extent of rotation of the cross-bars is limited by 30 the loops *g* and *g'*. The flat springs *d* and *d'* are fastened to the under parts of the cross-bars and bear against the upper surfaces of the inner extensions of the pads *c* and *c'*. The function of these springs is to keep the 35 hooks on the inner extensions of the pads always in contact with the carpet no matter what positions may have been assumed by the cross-bars. The two-part rods *b* *h* and *b'* *h'* are attached at their outer ends, respectively, to the cross-bars *a* and *a'*. Their inner ends are pivoted together by means of the bolt *p*. The upper sections *h* and *h'* slide over the lower sections *b* and *b'* when the pads *c* and *c'* are being spread apart, and the 40 parts are kept in place by the clamps *k* and *k'*, fastened to the upper sections, and by the clamps *l* and *l'*, fastened to the lower sections.

Both the upper sections of said two-part rods are provided with perforations *n* and *n'*, respectively, which also extend a short distance 45

into the upper surfaces of the lower sections and are so placed that when the extensions have been made in adjusting the spread of the pads pins *m* and *m'* may be placed therein to keep the sections from further movement. 55 The pieces *o* and *o'* are pivoted on the upper surfaces, respectively, of the inner ends of the upper sections *h* and *h'* at points a short distance inward from the pivot-bolt *p* and may be rotated on their pivots to throw their ends 60 into engagement with the under surfaces of the upper sections of the other two-part rod to keep the rods from sinking to a lower point than that desired.

When the proper extensions of the two-part rod have been made, the hook-studded under surfaces of the pads *c* and *c'* are placed in contact with the carpet, and when a bearing-down pressure is imposed upon the rods the hooks *f* and *f'* are forced into the carpet, 65 which is then stretched between the points of contact, and the curvature of the hooks prevents their becoming disengaged.

Having described my invention, what I claim as new, and desire to secure by Letters 70 Patent, is—

A carpet-stretcher consisting of two two-part rods whose sections are adjustable lengthwise upon each other, a bolt pivotally connecting the inner ends of said rods, a series of perforations extending through the upper into the lower sections of said rods, pins for holding said sections together, cross-bars at the outer ends of said rods, pads having their under surfaces studded with outwardly-curved brads, hinges connecting said pads with said cross-bars, loops fastened to said pads and arranged to limit the vertical movement of said rods, springs attached to said cross-bars and bearing against the upper 85 surfaces of said pads, and rotatable thumb-pieces on the upper surfaces of the inner ends of said rods, all substantially as shown and described.

Signed at Sumner, Iowa, this 7th day of 90 May, 1901.

ANDREW PARROTT.
